LEAD FORMING APPARATUS

Samuel Kuba, Allentown, Pa., assignor to Western Electric Company, Incorporated, New York, N. Y., a corporation of New York

Application November 29, 1954, Serial No. 471,806

4 Claims. (Cl. 140—71.5)

This invention relates to article forming apparatus particularly apparatus for forming leads for electrical units.

In the manufacture of certain types of electrical units such as electronic tubes, a plurality of lead wires are mounted in their respective positions in the initial stem structure for electrical connection with their respective elements of the tubes. Certain of the lead wires may remain in their initial equally spaced parallel positions while others must be bent into predetermined formations to adapt them for the mounting of other elements of the tubes. The formation of the selected elements must be maintained within a high degree of accuracy not only with respect to each other but with respect to the remaining leads.

The object of the invention is an apparatus which, although simple in structure, is highly efficient in accurately forming a projection of an article such as a lead of a tube or lamp stem structure.

With this and other objects in view, the invention comprises a fixed position nest to support an article having a projection and to position the projection with respect to forming elements supported for relative movement to cooperate in forming the projection.

In the present embodiment of the invention, the article has eight equally spaced initially parallel leads, three of which are longer than the remaining five and these three are acted upon simultaneously through a single control to actuate first and second elements in their respective order so that the first elements will cooperate with the nest to hold the selected leads and assist in the formation thereof while the second elements move the projecting portions of the selected leads into close engagement with forming portions of the first element to thereby produce the desired formations in the selected leads.

Other objects and advantages will be apparent from the following detailed description when considered in conjunction with the accompanying drawings, wherein:

Fig. 1 is a top plan view of the apparatus, a portion thereof being shown in section;

Fig. 2 is a sectional view taken substantially along the line 2—2 of Fig. 1;

Fig. 3 is an enlarged fragmentary vertical sectional view of the occupied nest with certain of the forming elements shown in closed position;

Fig. 4 is an enlarged isometric view of one of the forming units shown in open position;

Fig. 5 is a vertical sectional view taken along the line 5—5 of Fig. 1;

Fig. 6 is a fragmentary sectional view showing a portion of the nest with adjacent forming elements in open position, and

Fig. 7 is a view of the structure shown in Fig. 6 with the forming elements in closed position.

The apparatus as shown in Fig. 1 includes a support or table 10 having an annular housing 11 mounted thereon with a nest 12 disposed at its center to receive an article 14. In the present embodiment of the invention, the

2

article 14 is a stem structure for a given type of radio tube including eight leads 15 mounted in the glass stem structure and having their inner ends initially parallel with each other. By observing the central portion or nest 12 of Fig. 1, it will be noted that closed apertures or holes 16 are provided for five of the leads 15 while open apertures or recesses 17 are provided for the remaining three leads therefor. The main pocket of the nest 12 (as shown in Fig. 3) receives and supports the glass structure of the article or stem 14, the apertures 16 receive and locate accurately the five short leads of the article while the apertures or recesses 17 of the nest receive and locate the longer leads which are to be formed.

Like radially positioned forming units 18, 19 and 20 are under the control of a single actuating unit 21. It should be understood, therefore, that a description of the unit 18 with the actuating unit 21 may be applied also to the units 19 and 20. The unit 18 includes a first forming element 25 and a second forming element 26. The first forming element 25 is rectangular in general contour with the exception of its leading end 28 which has inwardly tapered surfaces 29 terminating at a flat front surface 30 which has an arcuate groove 31 extending vertically therein to partially conform to the lead which it is to form. An offset upper portion 33 of the element 25 has a leading surface similar in contour to the main leading surface of the element 25 with the tapered surfaces thereof terminating in a flat front surface wherein a semi-circular vertical groove 34, parallel with the groove 31 is disposed. The portion 33 is disposed in alignment with and adapted to be received in its respective recess 17 of the nest 12 to partially surround the adjacent lead 15 at the groove 34 and to cooperate with the nest in holding and forming the adjacent lead.

The second forming element 26 is hollow to movably receive the first forming element 25 and has tapered surfaces 35 in the main cavity thereof partially conforming to the tapered surfaces 29 of the leading end of the element 25 while a surface 36 and a semi-circular vertical groove 37 therein cooperate with the surface 30 and the groove 33 of the first element 25 to surround the adjacent lead 15 and cooperate in forming the lead.

In Fig. 5, the forming elements 25 and 26 of the unit 18 are shown disposed for sliding movement in one of the radial apertures 40 of the housing 11. The second element 26 is connected to an apertured piston 42 by a tube 43 while the first element 25 is connected to a piston 44 by a rod 45 which extends through an aperture in the central portion 46 of the cylinder structure and through the piston 42, the tube 43, and the adjacent portion of the second element 26 of the rearmost end of the first element where it is secured by any suitable means (not shown). The pistons 42 and 44 in their respective aligned cylinders 46 and 47 are shown more in detail in Fig. 1. In this figure, fluid lines 50 and 51 communicate with opposite sides of the piston 42 while fluid lines 52 and 53 communicate with opposite sides of the piston 43.

The single control unit is composed of a pair of commercially known valves mounted in tandem for actuation in timed relation with each other through the actuation of a single rockable element 55 mounted on a fixed position spindle 56. The unit 20 includes a valve 58 actuatable to control fluid lines 50 and 51 while a valve 59 controls fluid lines 52 and 53. The conventional inner piston like control elements of the valves 58 and 59 have plungers 60 and 61 normally urged outwardly to the right by their springs 62 and 63 but actuatable inwardly by their respective cams 64 and 65. In Figs. 1 and 2, the plungers 60 and 61 are shown free of their cams 64 and 65 re-

spectively. The cams 64 and 65 are of such sizes with their respective low and high portions 68—69 and 70—71 that the first and second elements of each unit 18, 19 and 20 will operate in a given sequence. For example, the valve 59 will be actuated in advance of the valve 58 during the first half cycle, that is, during closing of the elements to form the lead. However, during the next half cycle, that is, during opening of the elements to free the formed lead this action is reversed. The valves 58 and 59 are provided with air under pressure from supply lines 72—73 while they alternately make the fluid lines 50—51 and 52—53 exhaust lines communicating with a main exhaust line 74.

Considering now the operation of the apparatus, let it be assumed that the control element 55 with its handle 75 is in the position shown in Figs. 1 and 2 with the first and second forming elements 25 and 26 of the units 18, 19 and 20 in their open positions illustrated in Figs. 4 and 6. At this time, the operator may place an article in the nest with the leads in their proper positions including the five short leads in the apertures 16 and the three long leads in the apertures or recesses 17. The nest 12 serves to locate the article, particularly the leads which are to be formed, and has the recesses or open apertures 17 ready to cooperate with the portion 33 of each first element 25 of the units 18, 19 and 20. When the article is placed in the nest 12, the long leads, which are to be formed, extend downwardly into the open units 18 to 20 inclusive, as illustrated in Figs. 4 and 5. At this time, the operator may rock the control element 15 about the axis of its supporting spindle 56 to carry out a predetermined sequence of operations. The ramp or low portion 68 of the cam 64 will ride under the plunger 61 of the valve 59 to actuate the valve to cause air under pressure to pass through fluid line 53 while air is exhausted through fluid line 52 to move the piston 43 to the left to move the first element 25 into its forming position where the leading end thereof will be ready to form the adjacent lead 15 causing the portion 33 to move into close engagement with the lead with the groove 34 partially surrounding the lead. After this action has taken place, that is, after the first element has moved into its forming position, the second element will be actuated. The lapse of time between actions of the valves 59 and 58 and their sequence of operation are under the control of the single element 55, particularly the cams 64 and 65 thereon. When the valve 58 is actuated by its cam 65, air under pressure will be directed to the fluid line 50 and cause air to exhaust back of the piston 42 through fluid line 51 thereby moving the piston 42 to the right to move the second element 26 into its forming position shown in Figs. 3, 5 and 7. During this action of the second forming element in each unit 18, 19 and 20, the long leads 15 are bent outwardly determined by the portions thereof held by the projections 33 and the adjacent portions 17 and the nest, after which a predetermined length adjacent the ends of the long leads are bent parallel with the initial portions thereof and with the remaining short leads. This completes the forming portion of each operating cycle of the units 18 to 20 inclusive. The schematic fluid lines illustrating the connections between the valves 58—59 and their respective fluid lines 50 to 53 inclusive, illustrate the operative connection of the control unit 21 with the operating unit 18. These schematic fluid lines may be extended to the similar fluid lines of the units 19 and 20 to bring about simultaneous action of the first elements followed by simultaneous action of the second elements of these units during the closing or forming half of each operating cycle.

At the completion of the forming portion of each operating cycle, the operator returns the control element 55 to its starting position (shown in Figs. 1 and 2) and during this movement, the valve 58 will operate first by the cam 65 releasing the plunger 60 to direct air under pressure through line 51 and exhaust air back of the piston

43 through line 50. Following this action, valve 59 will be returned to its starting position by its spring 62, when the plunger 61 is released by its cam 64, to direct air under pressure through line 52 and exhaust air back of the piston 42 through line 53 to move the second element 26 into its open position as shown in Figs. 4 and 6. The article 14 with its formed leads may be removed from the nest and the next article to be formed may be located therein. The operation is rapid and efficient, requiring but a short time for the operator to locate each article accurately in the nest moving the single control element 55 from its normal position to its operating position and then back to its normal position during which time the forming elements of each of the units 18, 19 and 20 will move through their respective operating cycles to firmly hold and form the selected leads of each article and move back into open position so that the formed articles may be removed and a new article inserted in the nest.

It is to be understood that the above described arrangements are simply illustrative of the application of the principles of the invention. Numerous other arrangements may be readily devised by those skilled in the art which will embody the principles of the invention and fall within the spirit and scope thereof.

What is claimed is:

1. An apparatus for forming projections of articles comprising a support for the articles singly with the projection thereof extending at a given position from the support, forming elements supported for movement relative to the given position and relative to each other to cooperate in forming the projection of the article, and individual means to move the forming elements including aligned pistons, one having a central aperture therein, aligned cylinders for the pistons adapted to receive fluids under pressure to actuate the pistons, a tubular member connecting the apertured piston to its forming element, and a rod extending through the tubular member, the apertured piston and its cylinder to connect the other piston to its forming element.

2. An apparatus for forming projections of articles comprising a support for the articles singly with the projection thereof extending at a given position from the support, forming elements supported for movement relative to the given position and relative to each other to cooperate in forming the projection of the article, individual means to move forming elements including aligned pistons, one having a central aperture therein, aligned cylinders for the piston, adapted to receive fluids under pressure to actuate the pistons, a tubular member connecting the apertured piston to its forming element, a rod extending through the tubular member, the apertured piston and its cylinder to connect the other piston to its forming element, and means actuatable to cause the fluids under pressure to move the pistons and their forming elements in a given order.

3. A lead forming apparatus comprising a nest, adapted to support an article with an attached group of circularly positioned spaced leads, having recesses to locate selected leads of the group at forming positions, forming units having first and second forming elements, extending radially with respect to the forming positions of the nest, separate means for moving the first and second forming elements of each forming unit away from each other into open position to receive the selected leads in their respective recesses therebetween, and an actuator adapted first, to cause movement of the first forming elements into forming positions and to hold portions of their leads in their recesses, and second to cause movement of the second forming elements toward their first forming elements and relative to their recesses to form the leads.

4. A lead forming apparatus comprising a nest, adapted to support an article with an attached group of circularly positioned spaced leads, having recesses to locate selected leads of the group at forming positions, forming units having first and second forming elements extending ra-

dially with respect to the forming positions of the nest, a pair of aligned pistons for each forming unit, one having a central aperture therein, aligned cylinders for each pair of pistons adapted to receive fluids under pressure to actuate the pistons of each pair in reverse directions, a tubular member connecting each apertured piston to its respective second forming element, a rod extending the tubular member and the apertured piston and its cylinder in each forming unit to connect the other piston to the first forming element thereof, and an actuator adapted to cause the fluids under pressure to move the pistons in a given sequence, first to cause movement of the first forming elements into forming positions and to hold portions of their leads in their recesses, and second to cause movement of the second forming elements toward their first forming elements and relative to their recesses to form the leads.
